APPARATUS FOR ROLLING SECTIONS
HAVING TRANSVERSE RIBS

Hugo Seiferth, Dusseldorf-Oberkassel, Germany

Application October 24, 1930, Serial No. 490,956
In Germany December 19, 1929

4 Claims. (Cl. 80—19)

This invention relates to a device for rolling sections having relatively high transverse ribs or an irregular profile which comprises a roller and a rolling table which passes under said roller and is provided with recesses producing the irregular profile. In rolling such sections there is the disadvantage that the surfaces of the longitudinal side-edges of the ribs are not smooth and solid, more especially when the profile of the projections of the base section is of larger shape. The cause of this phenomenon has not been yet satisfactorily explained but it is surmised that it is connected with shrinking or is due to the fact that the enclosed air cannot completely escape.

The object of the present invention is to remove this objection.

According to the invention the said recesses of the rolling table are machined along their longitudinal lateral surfaces more and in another form than corresponds to the final shape and dimensions required. For this purpose the said recesses are provided with pyramidal or wedge-shaped raised parts, the apex and edge of which face the operating roller. The machining of the recesses may in each case extend to a part of the adjoining lateral edges of the base section. Where it is undesirable to have raised portions in the completed section they may be machined down. This construction has the advantage that very sharp edges are produced by the increased pressure that is produced by the said wedge-shaped or pyramidal raised parts.

The invention is diagrammatically illustrated by way of example in the accompanying drawings, in which:—

Fig. 1 is a cross sectional view through one of the completed bars showing in elevation a rib thereon.

Fig. 2 is a side elevational view thereof.

Fig. 3 is a longitudinal sectional view through the rolling apparatus.

Fig. 4 is a cross sectional view through the rolling apparatus shown in Fig. 3.

Fig. 5 is a cross sectional view through the fitting and rolling table the roller being shown in elevation.

Fig. 6 is a fragmentary longitudinal sectional view through the fitting the bar being shown in elevation.

Figs. 7, 8 and 10 show in section modified forms of the fitting for use in connection with the rolling table and the metal bar.

Fig. 9 is a longitudinal sectional view of the arrangement shown in Fig. 7 and

Fig. 11 is a longitudinal sectional view of the arrangement shown in Fig. 10.

Referring now, more particularly to the accompanying drawings, there is provided a profile bar 1 with a transverse rib 2 formed integral therewith. Prior to being completed as shown in Figs. 1 and 2 the bar is arranged in a fitting 3 having a transverse recess 4 at the bottom thereof in which the material is rolled so as to provide the rib or projection 2. The fitting is mounted in a rolling table indicated fragmentarily at 4', said table cooperating with the roller 5 (Figs. 3 and 4) substantially in accordance with the apparatus shown in my copending applications 455,835 filed May 26, 1930 and 506,965 filed January 6, 1931. The formation of the base of the fitting 3 is denoted by 7.

As shown in Figure 7 the fitting 3 is provided with a wedge-shaped raised part 6. This part produces an increased pressure on the surfaces of the longitudinal sides by its wedge-shaped formation, so that they are formed solid at the edges. Where the raised parts formed by this formation of the fitting 3 in the completed profile are undesirable or an obstruction, they can be subsequently machined down without difficulty.

In Figure 8 in addition to the wedge-shaped raised portions the lateral edges of the fitting are machined down further than corresponds to the final dimensions required for the section bar 85 whereby a satisfactory edge to the longitudinal lateral surfaces is obtained.

Figure 10 shows a further machining of the lateral surfaces up to a part of the base section, whereby a good solid edge is effectively secured 90 for the lateral surfaces.

The dot and dash lines show in each case the boundary lines of the finished section bar after the superfluous parts (see Figures 7 and 8) have been machined down.

I claim:

1. A device for rolling sections having relatively high transverse ribs or an irregular profile comprising a roller and a rolling table passing under said roller and being provided with recesses producing the irregular profile which are machined along their longitudinal lateral surfaces more and in another form than corresponds to the final shape and dimensions required, the said recesses being provided with pyramidal raised parts, the apex and edge of which face the operating roller.

2. A device for rolling sections having relatively high transverse ribs or an irregular profile comprising a roller and a rolling table passing

under said roller and being provided with recesses producing the irregular profile which are machined along their longitudinal lateral surfaces more and in another form than corresponds to the final shape and dimensions required, the said recesses being provided with wedge-shaped raised parts, the apex and edge of which face the operating roller.

3. A device for rolling sections having relatively high transverse ribs or an irregular profile comprising a roller and a rolling table passing under said roller and being provided with recesses producing the irregular profile which are machined along their longitudinal lateral surfaces and in the base of the section more and in another form than corresponds to the final shape and dimensions required, the machining of the said recesses extending to a part of the adjoining

lateral edges of the base section, the said recesses being provided with pyramidal raised parts, the apex and edge of which face the operating roller.

4. A device for rolling sections having relatively high transverse ribs or an irregular profile comprising a roller and a rolling table passing under said roller and being provided with recesses producing the irregular profile which are machined along their longitudinal lateral surfaces and in the base of the section more and in another form than corresponds to the final shape and dimensions required, the machining of the said recesses extending to a part of the adjoining lateral edges of the base section, the said recesses being provided with wedge-shaped raised parts, the apex and edge of which face the operating roller.
